ELECTRIC CONNECTOR

Stephen N. Buchanan, Westmoreland Hills, Md.,
assignor to Buchanan Electrical Products Corporation, Elizabeth, N. J., a corporation of New Jersey

Application July 2, 1948, Serial No. 36,567

2 Claims. (Cl. 173—328)

1

This invention relates to detachable connectors for interconnecting electrical conductors, particularly for use in automotive wiring.

In automotive wiring it is advantageous to divide the wiring harness into two or more parts that may be located in different parts of the car during the assembly operation. Subsequently it is necessary to interconnect these harnesses at least in part. It is important that at these points of interconnection a good electrical connection is made that will withstand vibration and any mechanical strain to which it may be subjected.

An object of my invention is to provide an improved detachable connector which will insure a good electrical connection and will withstand vibration and mechanical strain.

Other objects and advantages will appear from the description and drawings, in which

Fig. 1 is a side view showing my improved connector with one conductor connected to it and another conductor in position to be connected thereto;

Fig. 2 is a top view of the connector without the insulating sleeve;

Fig. 3 is a side view of the connector without the insulating sleeve;

Fig. 4 is a side view partly in section of the connector and insulating sleeve with a conductor connected at one end; and

Fig. 5 is a sectional view taken along the lines 5—5 of Fig. 3.

Referring to the drawings, Fig. 1 shows my improved detachable connector consisting of a connector or receptacle element 10 shown in dotted lines and an insulating sleeve 12. Two electrical conductors 14 and 16 are provided with plugs 18 and 20 respectively connected at their ends. The two conductors 14 and 16 are connected together by the insertion of the plugs 18 and 20 into opposite ends of connector or receptacle 10. Insulating sleeve 12 serves not only to insulate the connector 10 but also the portions of plugs 18 and 20 which extend beyond the ends of connector 10.

As may be better seen by reference to Figs. 2 and 3, connector element 10 is a double ended cylindrical receptacle with a central annular groove 22. An opening 24 is provided in groove 22 for a purpose that will be pointed out hereinafter. Three pairs of resilient fingers 26, 28, and 30 and 32, 34 and 36 are provided at each end of connector 10. The central or intermediate pairs of fingers 28 and 34 of each group 26 and 32 are provided with detents 38 and 40 respectively which extend inwardly to engage a

groove in a plug inserted in connector 10, such as groove 42 in plug 18 as shown in Fig. 4. Detents 38 and 40 have a smaller angle with respect to the axis of connector 10 at their forward ends than at their other ends. Plug 18, as shown in Fig. 4, has a cylindrical barrel portion 44, a reduced end 46 that is compressed or crimped into intimate engagement with the bared end of conductor 14, and a shoulder 48. When plug 18 is inserted in connector 10, the barrel portion 44 engages and expands fingers 26, 28, and 30. As plug 18 reaches its fully home position the detents 38 of fingers 20 extend into groove 42. Due to the smaller angle on the forward ends of detents 38, it requires less force to expand fingers 28 upon the insertion of plug 18 than upon its removal against the larger angle on the other ends of detents 38.

It is to be noted that the fingers 26, 28, 30, 32, 34, and 36 are separated by transverse slots and longitudinal slots as will be seen from an inspection of Figs. 2, 3, and 4. The slots separating the inner fingers 30 and 36 and the intermediate fingers 28 and 34 are of less extent than the slot separating the intermediate fingers 28 and 34 and outer fingers 26 and 32. The purpose of this structure is to provide greater flexibility for the outer fingers 26 and 32 and to render the inner fingers 30 and 36 relatively more rigid. This results in allowing the insertion of the plug 20 without encountering severe resistance until the inner fingers 30 and 36 are reached at which time these fingers will be expanded and will grip the plug 20 with considerable force. This structure is particularly advantageous over one in which all of fingers have the same degree of flexibility in that the assembly of the plug therewith is materially facilitated. In addition to facilitating such assembly this structure also insures that the plug 20 will be firmly retained in position in the connector 10 in order to provide a firm mechanical connection as well as a low resistance electrical connector.

Insulating sleeve 12 is formed of a relatively rigid plastic material such as one of the vinyls or one of the cellulosics and has a cylindrical exterior. The interior bore of sleeve 12 is slightly larger than the exterior diameter of connector 10 except at the two ends where the bore is enlarged to accommodate the shoulder 48 of plug 18. Sleeve 12 in cylindrical form is located over connector 10 with the ends of connector 10 equidistant from the ends of sleeve 12. By the application of heat and pressure an inwardly extending annular ring 50 conforming to and in

close engagement with groove 22 of connector 10 is formed at the center of sleeve 12. In the forming of ring 50 a portion 52 thereof is projected into the opening 24 of groove 22. The ring 50 in engagement with groove 22 prevents axial movement and the portion 52 projecting into opening 24 prevents rotary movement between connector 10 and sleeve 12. The end portions of sleeve 12 extending beyond the ends of connector 10 serve as guides for the insertion of plugs 18 and 20 into engagement with connector 10, but even more important, they cooperate with shoulders 48 and 49 of plugs 18 and 20, respectively, to prevent the plugs from being removed at an angle to the axis of connector 10 which might cause one or more of the pairs of fingers to be expanded beyond the elastic limit and produce permanent deformation which would reduce the holding force and electrical contact between the connector and a plug subsequently inserted.

What is claimed:

1. An electrical connector of the character described including a double ended cylindrical receptacle having a central annular groove with a small radial opening, two groups of three pairs of fingers adapted to receive and resiliently engage a plug inserted from each end of the connector, the central pair of fingers of each group having inwardly extending detents to engage and hold a plug in the connector, said fingers being separated by transverse slots, the slots separating the inner pairs of fingers and the central fingers being of less extent than the slot separating the outer pairs of fingers and the central fingers whereby the outer pairs of fingers are relatively more flexible than the inner pairs of fingers, and a relatively rigid insulating sleeve for said receptacle having an inwardly extending annular ring portion engaging said groove and having a portion extending into said radial opening to lock said sleeve against axial and rotary movement with respect to said receptacle and having a portion extending beyond the receptacle to guide the plug into engagement with the receptacle and prevent removal thereof at an angle to the axis of the connector whereby excessive radial movement and permanent deformation of said fingers will be prevented.

2. An electrical connector of the character described including a double ended cylindrical

receptacle having a central annular groove with a small radial opening, two groups of three pairs of fingers adapted to receive and resiliently engage a plug inserted from each end of the connector, the central pair of fingers of each group having inwardly extending detents to engage and hold a plug in the connector, said detents having a smaller angle at their forward ends than at their other ends whereby the force required to remove the plug is greater than the force necessary to insert it in the connector, said pairs of fingers being separated by transverse slots, the slots separating the inner pairs of fingers and the central pairs of fingers being of less extent than the slots separating the outer pairs of fingers and the central pairs of fingers whereby said outer pairs of fingers are relatively more flexible than said inner pairs of fingers and a relatively rigid insulating sleeve for said receptacle having an inwardly extending annular ring portion engaging said groove and having a portion extending into said radial opening to lock said sleeve against axial and rotary movement with respect to said receptacle and having a portion extending beyond said receptacle to guide a plug into engagement with the receptacle and prevent removal thereof at an angle to the axis of the connector whereby excessive radial movement and permanent deformation of said fingers will be prevented.

STEPHEN N. BUCHANAN.
